UNITED STATES PATENT OFFICE.

WILLIAM J. KAPPEL, OF MILWAUKEE, WISCONSIN.

SHOE-COUNTER FLEXOR.

1,424,166.

Specification of Letters Patent. Patented Aug. 1, 1922.

Application filed March 8, 1921. Serial No. 450,731.

To all whom it may concern:

Be it known that I, WILLIAM J. KAPPEL, a citizen of the United States, and resident of Milwaukee, in the county of Milwaukee, 5 and State of Wisconsin, have invented certain new and useful Improvements in Shoe-Counter Flexors; and I do hereby declare that the following is a full, clear, and exact description thereof.

10 My invention refers to machines or presses for softening shoe counters, and it has for its object to provide a simple, economical and effective device for forming the functions mentioned, the same being 15 so constructed and arranged that it can be manufactured in two parts, and wherein machine work is eliminated, to thus reduce the cost of the structure materially, whereby it can be sold to the trade at a minimum figure, 20 it being borne in mind that such machines must be simple in construction and developed in such manner that they will not readily become out of order through rough usage.

25 With the above object in view, the invention consists in certain peculiarities of construction and combination of parts, as are hereinafter set forth with reference to the accompanying drawings and subsequently 30 claimed.

In the drawings:

Figure 1 represents a side elevation of a shoe counter softening machine embodying the features of my invention.

35 Figure 2 is a cross-sectional plan view of the same, the section being indicated by line 2-2 of Figure 1, and

40 Figure 3 is a detail cross-section through the counter gripping members, the section being indicated by line 3-3 of Figure 1, the said view showing the relative position of the anvil and gripping fingers associated therewith.

45 Referring by characters to the drawings, 1 represents the base plate of a bracket, which bracket is formed with a standard 2, the same terminating at its upper end with an offset arm 3, the end of which forms a fixed anvil 4. The anvil is shown preferably 50 round in cross-section and it is encased in a flexible tube section 4' to thus protect the leather of a shoe counter from injury. The base of the bracket is adapted to be permanently secured to a support. The post is 55 apertured directly under the arm 3, for the

reception of a pivot bolt 5, which bolt serves as a fulcrum for fork arms 6-6, as shown in Figure 2, the same being apertured for the reception of the bolt 5. The fork arms at one end are merged into a hand lever 7, 60 and the forward ends of said fork arms terminate with pressure fingers 8-8, which fingers, as shown in Figure 3, are oval in cross-section, the same being arranged under and parallel to the anvil and being spaced apart 65 in such manner that the inner convex walls thereof will approach corresponding walls of the anvil when the lever is manipulated to effect a shoe counter softening operation.

70 It will be observed that the fork members 6-6 which extend below and parallel with the bracket arm 3 are of such dimensions and length, as to render them flexible under strain. Hence, when they are forced 75 toward the anvil they will exert positive squeezing action upon the shoe counter worked upon, while at the same time their resiliency will permit them to spread apart 80 slightly so as to perform somewhat an ironing function.

85 From the foregoing description, it will be seen that in operation the shoe counter is slipped over the pressure fingers, and if the shoe is of the boot type, there is ample room 85 for the top thereof, due to the fact that a long throat effect is had between the fingers and arm 3 of the bracket, whereby clearance of the top is effected.

After the shoe is inserted in place, the 85 operator simply presses the hand lever 7 downwardly, repeating this operation indefinitely and at each movement of the lever the counter, which is squeezed between the anvil and the fingers, will be worked or 95 hammered back and forth so as to soften it, while at the same time the counter or shoe can be rolled so as to change the point of contact between the fingers and anvil. Hence, the counter is thoroughly softened 100 throughout its entire semicircular area, quickly and effectively.

Obviously, while I have shown a simple lever for obtaining the desired pressure between the working parts of the machine, I 105 may utilize in connection with the lever a cam or screw element for increasing the pressure if desired.

While I have shown and described a simple exemplification of my invention in all of 110

its details it is understood that I may vary certain structural features within the scope of the claims.

I claim:

- 5 1. As a new article of manufacture, a base bracket having an overhanging arm terminating with a fixed cylindrical anvil, and a forked lever pivoted to the arm, the fork terminating with pressure fingers parallel 10 the anvil and spaced apart equal distances from a vertical alignment through said anvil.
- 15 2. As a new article of manufacture, a supporting bracket having an overhanging arm, the arm terminating with a circular anvil, and a lever in pivotal union with the bracket, the lever having a fork projecting therefrom in alignment with the arm, the fork terminating with pressure fingers

adapted to engage the opposite walls of the 20 anvil, and the said fork being capable of yielding under such strain of engagement.

3. As a new article of manufacture, a bracket having an overhanging arm terminating with an anvil, circular in cross-section, a yielding jacket tube fitted about the anvil, and a forked lever in pivotal union with the bracket, the forked ends being extended parallel with the bracket arm, and said fork members terminating with fingers 30 having convexed inner walls adapted to engage the walls of the anvil jacket.

In testimony that I claim the foregoing I have hereunto set my hand at Milwaukee, in the county of Milwaukee and State of Wis- 35consin.

WILLIAM J. KAPPEL.
